UNITED STATES PATENT OFFICE

2,119,516

AIR COOLED DIE-HOLDER

William J. Schuster, Cleveland, Ohio, assignor to
The American Steel and Wire Company of New
Jersey, a corporation of New Jersey

Application September 12, 1936, Serial No. 100,530

8 Claims. (Cl. 205—25)

This invention relates to die-holders and more particularly to air cooled die-holders.

When wire is drawn through a die, a great amount of friction results. This friction is evidenced in the form of heat which must be dissipated in order to prevent damaging the die or the wire being drawn, or both. The problem of dissipating the heat generated in the wire drawing operation is magnified by the desire to use the die for relatively long periods and at high drawing speeds.

The present invention has for its object the provision of means for dissipating the heat in the die-holder with such effectiveness that the die may be used for high speed continuous wire drawing without overheating.

The above and other objects will be apparent as the description proceeds and by reference to the accompanying drawings, in which:

Figure 1 is a plan of a die-holder constructed in accordance with my invention.

Figure 2 is a sectional elevation taken on line II—II of Figure 1.

Figure 3 is an elevation taken on line III—III of Figure 2.

Figure 4 is an elevation of the quickly releasable means mounting the die-holder on the base.

Referring to the accompanying drawings, the letter H refers generally to a die-holding member which is an integral casting and which is mounted by any convenient means, for example, by a base plate 4. To assist the base plate 4 in properly supporting the member H, it is provided with a circular recess 6 in its upper surface and a circular boss 7 directly underneath the recess 6. The base plate 4 is usually mounted on a table support 8 with the boss 7 extending into a hole in said support. Preferably, bolts 10 and 12 received in a hole 14 and slot 16, respectively in opposite ends of the base plate 4, are employed to secure the base plate 4 to the support 8. By mounting the base plate 4 in this manner, it can be moved through a small arc using the bolt 10 as a center to properly align the member H with a wire block (not shown).

An aperture 18 is provided in the base plate 4 at the bottom of the recess 6, and is threaded at its lower end to receive a pipe 20. The pipe 20 is adapted to be connected with any suitable means for supplying it with compressed air so that a stream of air can be forced into the aperture 18. Circular recesses 19 and 21 extend into the base plate 4 in diagonally opposite portions thereof.

The member H has flanges 24 and 25 terminat-

ing in arms 24^a and 25^a, respectively, and is provided with a boss 27^a on its bottom surface which snugly fits in the recess 6 on the base plate 4. The inner surface of two of the diametrically opposite arms 24^a and 25^a of the flanges 24 and 25 are provided with semicircular recesses 26 and 27 which overlie apertures 22 and 23 in the base plate 4, which apertures have shoulders intermediate their ends. The other pair of arms 24^a and 25^a are provided with centering bolts 28 and 29 which fit in the recesses 19 and 21 when the member H is positioned on the base plate 4. The centering bolts 28 and 29 make the member H take and maintain exactly the same position each time it is secured to the base plate 4.

In order to firmly hold the member H to the base plate 4 by quickly releasable means so that other similar die-holders can rapidly be substituted for the member H, bolts 30 are provided which extend through the apertures 22 and 23 of the base plate 4 and the recesses 26 and 27 of the flanges 24 and 25 when they overlie the apertures 22 and 23. The bolts 30 have flattened ends to which are pivotally secured levers 32 having U-shaped heads and cammed bottom surfaces adapted to releasably bear upon the flanges 24 and 25. The bolts 30 are preferably retained in their vertical positions, even though the flanges 24 and 25 are removed from underneath them by means of flanges 33, on the bolts 30, which bear upon the shoulders in the apertures 22 and 23.

When the levers 32 are in their vertical positions, enough clearance is provided between them and the base plate 4 so that the flanges 24 and 25 and the bolts 28 and 29 do not strike the base plate 4 or otherwise interfere in positioning the member H on the base plate 4. The clamping action of the bolts 30 and the levers 32 can be adjusted by varying the positions of the nuts on the ends of the bolts 30. As the bolt 30 and thereby the levers 32 are held up, it is quite easy to put the boss 27^a of the member H in the recess 6 of the base plate 4 so that by rotating the member H the recesses 26 and 27 engage the bolts 30, and the centering bolts 28 and 29 fit in the recesses 19 and 21. Then the member H is readily secured in place by moving the levers 32 down so that their cam surfaces bear upon the flanges 24 and 25.

The member H has a rectangular body portion 36 which has the flanges 24 and 25 on its longitudinal edges. The body portion 36 has the boss 27^a on its bottom surface and an aperture 38 extends through the boss 27^a. This aperture 55

enlarges after extending into the body 36 and continues to nearly the top of the body portion 36. The body portion 36 has several parallel fins 39 extending into the aperture 38. The fins 39 preferably are, as shown, on the roof of the aperture 38 and extend the length of the body portion 36, directly underneath a recess 40 in the center of the top surface of the body portion 36.

In the roof of the body portion 36, and extending from the aperture 38 on both sides of the fins 39, ports 42 slope towards and terminate adjacent the recess 40. The number and spacing of the ports 42 can be varied as desired. The corners of the aperture 38 are smoothly curved so that when air is forced into it by way of the pipe 20 and aperture 18, the air strikes the fins 39 and then flows out of the aperture 38 through the ports 42.

There are two parallel upright arms 44 and 46 formed integrally on the body portion 36. These arms are on the upper longitudinal edges of this body and are somewhat shorter than these edges. Each of the arms 44 and 46 has an integral portion which resembles a section of a frustum of a rectangular pyramid extending down from its top on its inside surface. This provides a flat rectangular section which is thicker than the edges of the arms 44 and 46 and tapers down to the edges and at the bottom to the edge thickness. Apertures 48 and 49 are in this section and on its center line. The apertures 48 and 49 are aligned with rectangular apertures 50 and 51 which are also in the arms 44 and 46. The arms 44 and 46 have semicircular recesses 52 in their tops and substantially right angle sections 54 cut out of their top corners.

In order to secure a multiple-hole die 60 in the member H, members 62 and 63 are provided which have cylindrical portions 64 and 65 at one end extending perpendicularly to said members and adapted to sit in the recesses 52. The members 62 and 63 have tapped bores 66 and 67 extending longitudinally through the cylindrical portions 64 and 65. On the other end of the members 62 and 63 there are solid cylinders 68 and 69 which are adapted to fit into and extend through the recesses 48 and 49 of the arms 44 and 46. The ends of the cylinders 68 and 69 are tapered so that they can fit into the large ends of the die-holes in the die 60. Then, as the recess 66 is provided with left-handed threads and the recess 67 with right-handed threads a rod 70, whose surfaces adjacent its ends are correspondingly threaded, can engage or disengage both members 62 and 63 by turning it in one direction. The rod 70 has a square section 71 of smaller dimensions than the diameter of the rod 70 at its center wide enough for a wrench to fit thereon. Then, by turning the rod 70, the members 62 and 63 engaged with it can be moved away from or towards each other as desired. This, of course, also moves the cylinders 68 and 69 away from or towards each other as they are integral with the members 62 and 63.

The multiple-hole die 60 sets in the recess 40 of the member H. In order to fixedly secure the die 60 to the member H, the cylinders 68 and 69 are made to move towards each other, by turning the rod 70, and bear upon the die 60 so that the end of one cylinder engages the large end of a die-hole. The cylinders 68 and 69 fixedly secure the die 60 in place by this pressure and, in addition, act to center the die-hole to be used in the member H. The centering action is produced as the die-holes are in vertical alignment and the

cylinders 68 and 69 are made to engage with and position the upper hole 60. This then exposes a die-hole through the apertures 48 and 49.

After positioning the die, wire can be drawn through the exposed die-hole in the direction indicated by the arrow in Figure 2 of the drawings. Then, as the arm 46 and the body portion 36 of the member H are in contact with the die 60, heat generated in the wire drawing operation is conducted to it from the die 60, as the member H has no other means heating it. Heat is also conducted to the arms 44 and 46 by the cylinders 68 and 69 which are in contact with the die 60. The stream of air forced into the aperture 38 strikes the fins 39 and absorbs a large quantity of heat from the member H. This heat taken from the member H thereby cools the die 60 as it can constantly transfer heat to the member H from which the heat is dissipated by the above described method. The stream of air against the fins of the member H tends to keep this member at a substantially lower temperature than the die 60 so that heat readily flows to it from the die 60.

An additional cooling effect is secured when the air exhausts through the ports 42 as it is made to flow against the die 60. The air from the center ports also tends to cool the drawn wire as it is directly in the air stream from the center ports.

It will be appreciated that the scope of the invention is not limited to the specific form illustrated and described but is actually defined in the appended claims.

I claim:

1. In a die-holder for a multiple-hole die, the combination of movable means adapted to bear upon a multiple hole die, a die-holding member for supporting said die and means, said member having a body portion provided with an aperture, a base for said die-holding member, quickly releasable means for mounting said member on said base, a support for anchoring said base but adapted to permit limited lateral movement thereof, and means permanently fastened to said base for circulating air through said aperture in said body portion.

2. A die-holder including the combination of a multiple-hole die, means adapted to bear upon said die, a die-holding member for supporting said die and means, said member having a body portion provided with an aperture, a base for said die-holding member, means for mounting said member on said base, a support for anchoring said base but adapted to permit limited lateral movement thereof, and means permanently fastened to said base for circulating air through said aperture in said body portion.

3. In a die-holder, the combination of a multiple-hole die, adjustable holding and centering means adapted to bear upon the opposed faces of said die and positively engaging therewith, a die-holding member for engaging with said means adjacent both faces of said die and for supporting said die and means, said member having a body portion provided with an aperture, a base for said holding member, means mounting said member on said base, a support securing said base, and means permanently fastened to said base for circulating air through said aperture in said body portion into contact with the opposed faces of said die.

4. An air cooled die-holder comprising a body portion provided with an aperture therein, spaced parallel arms integral with and extending from said body portion, movable members adapted to move together to secure a die between said arms

- and means for circulating air through said aperture and exhausting it across both faces of said die.
5. An air cooled die-holder comprising means for bearing upon opposed faces of a multiple-hole die and forming a unit therewith, a die-holding member adapted to engage with said means adjacent both faces of said die and thereby positively positioning and clamping said die, said member being provided with a cooling chamber, means for anchoring said member, means for circulating air through said chamber and directing streams of air across both faces of said die so as to lower the temperature thereof.
10. 6. An air cooled die-holder comprising means for bearing upon opposed faces of a multiple-hole die, a die-holding member adapted to engage with said means and thereby positively position said die, means for circulating air through said member and directing at least one stream of air across both faces of said die so as to lower the temperature thereof.
- 15
- 20

7. An air cooled die-holder comprising a body portion having an aperture therein, spaced parallel arms integral with and extending substantially normally from said body portion, clamping means carried by said arms and adapted to be moved substantially normally to the planes of said arms, said clamping means being constructed and arranged to engage with a multiple-hole die and positively position it between said arms, and means for circulating air through said aperture and exhausting streams of air across the faces of the die.

8. An air cooled die-holder comprising a body portion, spaced parallel arms integral with said body portion, clamping means carried by said arms, said clamping means being constructed and arranged to engage with a multiple-hole die and positively position it between said arms, and means for circulating air through said body portion and exhausting streams of air across the faces of the die.

WILLIAM J. SCHUSTER.
